UNITED STATES PATENT OFFICE.

EDOUARD WILFRID BUEQUET, OF MONTROUGE, FRANCE.

METHOD OF CONSTRUCTING METAL WHEELS.

Application filed March 7, 1924, Serial No. 697,649, and in France March 15, 1923.

The qualities which are looked for in a fixed or removable motor car wheel are as follows:

The facility of cleaning and the suppression of interspaces capable of being oxidized.

The lightness which improves the suspension in reducing the weight of the non-suspended masses.

10 The resistance to lateral stresses which tend to break the wheel, namely when an obstacle preventing skidding forces the wheel to support the whole of the centrifugal power.

15 The stiffness that is to say unnoticeable value of the elastic distortions for very large strains.

20 The absence of jars or vibrations; the wheels frequently revolve at the rate of over 800 revolutions per minute, and if jars similar to those of a bell begin in a sheet iron wheel with a single cone for example, and if the rate of revolution is sufficient, these jars can attain such an amplitude that the 25 wheel acting in the same manner as a heavy excentered fly wheel subjects the parts of the vehicle to a very detrimental wear.

The rigidity of the whole and the lightness of the periphery avoid the jars.

30 The pneumatic imparts a sufficient transverse elasticity to the connection with the ground.

The invention consists in providing a wheel presenting these qualities.

35 In the accompanying drawing:

Figures 1 to 17 are diagrammatic views illustrating the principles of constructing both spoked and disk wheels;

Fig. 18 is a vertical section of a wheel 40 embodying one form of the invention;

Fig. 19 is a side view of the same;

Figs. 20 to 26, inclusive, illustrate the variable profile of the ribs formed in the discs prior to subjecting them to the step 45 of stretching;

Fig. 27 is a vertical section illustrating one method of forming the cheeks and hub from a cylinder;

50 Figs. 28-33 inclusive illustrate the method of connecting the discs to the wheel rims; Figs. 31 and 32 showing rims formed by the discs.

Figs. 34 to 37 inclusive illustrate several

means for spreading the hubs of the wheel.

In Figure 4 A designates the rim which is firmly connected with two sheet iron cones R and R' the metal of which can be stretched or spread in removing the two halves B and C of the extensible hub the one from the other by means of the screw V.

The principles upon which the construction of such a wheel are based will clearly appear from the following description:

Supposing a bicycle wheel with metal spokes which is shown in the diagram of Figs. 1 and 2.

The rim A A' is connected with the hub B, C through wires D, E, F, G, which can be shortened by means of spanners or spreaders H, I, J, K.

Its lateral rigidity can be determined by the value of the couple formed by the forces P and P' (Fig. 2) which is necessary in order to incline the axis to the plane of the wheel which is supposed to be fixed.

If the strains P and P' gradually increase, the tensions of D and F will gradually increase, those D and G will diminish; however, the wheel is not submitted to any noticeable distortion, the lengths of the sides of triangles A B C and A' B C being practically invariable.

If the forces P and P' continue to increase, the tensions of E and G gradually decrease until they are null; at this moment, the distortions are still unnoticeable but if forces P and P' further increase, the tensions of G and E will become negative and the wires which have practically no resistance to compression will assume a sinuous form (Fig. 3); the triangles A B C and A' B C which have a curvilinear side are no longer undistortable, the rim on being no longer geometrically maintained about a circle will be distorted, become sinuous, is shortened, the spokes are slackened and allow the axle to incline itself.

A wheel with metal spokes therefore practically begins to distort itself only when the initial tension of the spokes such as G and E has decreased as far as to become null; if the initial tension is very large, the strain which is required for determining the distortion is also very large. In a wheel in which the spokes are not spread, the sides of the triangles would lose their rectilinear

form and the important distortion would begin with very small values of the strains P and P' .

- The cyclist causes his rim to describe a perfect circle in acting upon the length of the spokes; the position of the rim with reference to the axle is therefore geometrically determined by the length of the spokes. The pull of the spokes which tends to reduce the circumference of the rim imparts to the latter a pressing strain. The rigidity or stiffness of the rim does not depend upon the value of the moment of inertia of its section but upon the fact that if the axle is fixed every point is determined in the space by the length of the spokes to such an extent that it is possible to saw at several points the rim of a spread wheel without it losing its rigidity.
- In the usual wheels, the spokes are of a limited number and the traction which is exerted upon the rim is localized at the fastening points which makes it necessary to reinforce these points or to give to the whole of the rim an exaggerated size to allow the same to resist the tearing action of the spoke-heads and to prevent bending between two fastening points. This would not be the case if the number of spokes was indefinitely large, their pull would be evenly distributed: the rim would then be submitted only to the pressing of strain, its section could be smaller and everything being equal the moment of inertia of this section would be theoretically neutral: the increase of the number of spokes therefore permits the weight of the rim to be reduced.
- If one had to saw the hub of a wheel having span or spread spokes, one would feel, when trying to spread apart the two parts thereof, a resistance which would be equal to the resultant according to the axis of tension of the spokes.
- If by means of a screw bearing upon one of the parts of the hub and screwing into the other part, (Fig. 4) or by any other means, the ends of the hub were forcibly spread apart, the spokes would become longer and their tension would increase.
- Therefore it is possible to do away with the spreaders or stretchers and to spread the wheel by extending the hub. One can also conceive a wheel provided with spokes of rectangular section uniform over the whole of their length, and in a sufficient number to allow them to come into contact with one another in the vicinity of the hub (Fig. 5). The spokes may without changing either their length or the surface of their section, be flattened and consequently widened in the direction of the rim of the wheel (Fig. 6) and narrowed in the direction of the axis. They can be widened to such an extent that every one will occupy the space existing between two consecutive spokes (Fig. 7). We

may obtain a conical web or sheet of metal the thickness of which increases towards the center and all the molecules of which work under traction at a uniform rate which can be the maximum allowable, for the adopted metal, as by hypothesis, the section of the surface of every spoke has not been altered from one end to the other and the same applies to its length and initial tension.

For a determined value of the sum of all the radial tractions or pulls, the weight of such a cone corresponds to the minimum.

If the two parts of the hub are then spread apart, the spokes expand, and as a consequence their width is slightly reduced; a small interval is formed between the spokes (Fig. 8).

Supposing a cone, which is firmly fixed to the rim is divided into segments as the previous one but formed of sheet-iron of uniform thickness (Figs. 9 and 10) and upon which concentric circles are traced.

If the hub is acted upon to increase its length, and to extend or elongate the spokes to such a degree as to considerably exceed the limit of the elastic distortions, the pulling strain supported by every strip is uniform over the whole of the length but the section it presents for resisting the same decreases from the periphery to the center; the parts situated in the area of the hub are extended and consequently are further shrunk and the spaces between them are larger (Figs. 11 and 12).

Then by shortening the hub this open-work cone is crushed so that the spaces are contracted until the edges join thus forming a revolving surface with concave generating lines (Fig. 13).

The circles traced upon the cone show a reduced diameter whereas they are now formed of small arcs placed end to end and the length of every one of these arcs has been reduced during the drawing of the metal.

In extending the hub gradually, it would appear that the generating lines would straighten themselves, the circles would become larger and the slots would become wider until they have reassumed their original length (Figs. 11 and 12).

If instead of a cone divided into segments or sectors as previously described, a similar cone had been drawn by an extension of the hub, this cone being formed of a single sheet-iron web without any interruptions over which the sectors would have been simply traced, one would have obtained a revolving surface (Fig. 14) intermediate between the surface represented in Fig. 13 (and in dotted lines in Fig. 14) and that of a higher cone with straight generating lines (in dotted lines Fig. 14) but nearer however to the first surface.

In fact the extensions of every sector and

the resulting shrinkings would have nearly retained the value they had in the case of the slit cone, the direction of the pulling stresses in the curved generating line being little different from that of the chord.

5 The circles traced about the cone tend therefore to shrink.

But, on the other hand, the pull or traction tends to straighten the generating line, accordingly 10 the circles will shrink to a lesser extent by virtue of this fact.

However, this tendency to straightening will never compensate the shrinking stress of the circles, whereas it becomes null when 15 the curvature of the generating line becomes very small; it will always compensate the same but to a very small extent; as its value is small comparatively to the shrinking stress under the influence of drawing.

20 In conclusion, if a cone made of sheet iron of a uniform thickness is taken, and the height of the cone is increased by force it will be possible to obtain a revolving surface with a more accentuated curvature towards 25 the center; a similar form is observed when a cylindrical punch is pressed against the middle of a metal plate which is firmly maintained at its edges (Fig. 15).

A wheel constructed by means of such surfaces 30 would not be rigid as the axis could assume different inclined positions over the plan of the rim, the same being maintained only by curved spokes the length of which is capable of varying when being straightened or curved (Fig. 16).

As the rim is not geometrically fixed in the space with reference to the axis, the same could distort itself for a similar reason.

The metal which is situated near the hub 40 would be submitted to continuous alternate bendings.

For the purpose of allowing a cone, especially if it is of a uniform thickness, to extend its generating lines and to stretch them 45 by an extension of the hub, it is necessary to allow the metal to expand to a considerable extent in the direction which is normal to the generating lines so as to fill the empty spaces which tend to form themselves between the spokes as a result of the same becoming thinner; to this effect, the original 50 cone must have been provided with hollow or projecting grooves which in expanding during the straightening operation (Fig. 17) 55 will supply the metal as required for filling the above-mentioned interspaces.

The extension of their profile will, for every distance from the center be sufficient to fill up these spaces.

60 They can, when expanding, disappear partially or totally, this may be assisted by hammering, pressing or other process which is needed, to allow the tension of the metal to be retained in the direction of the circumference so as to facilitate a subsequent

extension of the radial web. A pressing or rolling operation acting in the same way as the crushing by means of a hammer provided with a narrow cylindrical head of small diameter, the generating lines being placed 70 parallel with those of the cone would expand the metal normally to the generating lines and could replace or assist the action of the grooves.

A mechanical action (pressing and the like) 75 will facilitate the straightening of the generating lines.

A wheel made of such conical dress is rigid, as any point of the rim cannot be considerably displaced with reference to the 80 axis except under the action of considerable strains.

Figure 18 shows in section a wheel for motor-car Fig. 19 being a front view.

This wheel is composed of a rim A made 85 of profiled steel for receiving the pneumatic tyre and of two sheet iron conical cheeks R and R' whose edges have been raised and which are secured to the rim by means of milled rivets. The contact surface 90 of the two cones and their joint with the rim are then hard-soldered, but all the usual processes of riveting, hard-soldering, autogenous welding or electrical welding, and the like, can be used. The joining of the 95 cones to one another must be sufficiently strong to prevent them from sliding against one another. These cones or cheeks are each provided with 12 grooves which are hollow or V-shaped (Fig. 19).

100 The hub made of stamped steel comprises a socket B provided with a tapered bore through which the axle passes, and a ring C, sliding with friction upon the socket. Every one of these parts is provided with a shoulder to which is secured the cheeks by rivets and hard-soldering like the rim; six screws with hexagonal heads V are screwed into the parts H and bear upon the part C. A wire-ring passes through holes drilled in 110 the heads of the screws for preventing the loosening of same.

The conical cheeks are spread or stretched as above explained, by acting upon the screws which move the two parts from one 115 another.

Many other arrangements may be adopted: the grooves can be hollow or projecting, the number and the projection of these grooves can vary, they can be so close to one another as to form a continuous corrugation. They can be similar, or alternatively long and short. The cones are made by means of the usual processes used in boiler-smith's work, chasing, punching, milling or rolling of sheet-iron cut according to the evolution of the cone and of the grooves by autogenous welding or any other joining, along a generating line, and the like.

120 Their height before straightening can be 125

as small as desired; they can present the form of flat disks provided with grooves according to the current processes of stamping, or rolling by means of corrugated 5 rollers and the like.

The grooves can be such that the cone being once spread or stretched, they will completely disappear; on the contrary, they could be of a superabundant extension and 10 show a variable profile forming permanent ribs which will add to the rigidity of the generating lines; Figs. 20, 21, 22, 23, 24, 25 and 26 show some possible forms.

They can be flattened or reinforced at 15 their ends so as to allow the fastening of the sheet iron.

Their form can contribute to improve the appearance of the wheel.

The height of the cones, the nature and 20 thickness of the metal, the distribution of the thicknesses, the number and the shape of the grooves, can differ from one cone to the other.

The thickness of the metal can decrease 25 towards the periphery, if the maximum of lightness is desired—on the contrary the thickness can be uniform if it is considered that the excess of thickness of the metal in the vicinity of the rim assists in reinforcing 30 the area submitted to the jerks or shocks of the road. If the connection with the rim is a very intimate one, the same being obtained through hard-soldering for instance, said connection can be weaker; Figs. 28, 29, 35, 30, 31, 32 and 33 show some modes of connection.

The rim will be obtained by rolling a drawn profiled part through milling and the like or through dressing or working of the 40 cone edges.

During the stretching or spanning of the wheel, the expansion of the metal fibres can largely exceed the limit of elastic distortion and thus cause a cold-hammering through 45 traction which will increase the resistance of the metal.

Instead of spreading the cones by maintaining their bases into contact and by moving the apexes apart, it will be possible to 50 maintain the apexes apart and to bring the bases nearer together by means of presses or any other means, this being specially the case if the cones have been provided at their periphery with reinforcing or straightening 55 parts taken from their mass or connected therewith and capable of resisting the strains which tend to reduce the diameter thereof. They will then be fixed in this position through the usual processes of bolting, riveting, hard-soldering, and the like.

This mode of tensioning is particularly to be used when it is desired to obtain a total expansion which is larger than the one 60 which would be possible by the mere spreading of the hub; the same will then only be

used for achieving the stretching or spreading.

This process would also be used in the case where the two cones are formed by flaring both ends of a tube, the part which 70 remains cylindrical constituting the hub; Fig. 27 shows the successive forms at different stages of the process; the distribution of the thicknesses, the flanges and the grooves can be obtained by rolling between revolv. 75 ing rolls of a suitable profile.

The tension of the conical cheeks can be a definitive one and the hub can be unexpansible; the cheeks can be made adjustable at the periphery by bringing the bases 80 nearer to the apexes instead of removing them there from.

The spreading of the hub can be obtained by any suitable means for example by means of screws, the externally projecting heads 85 of which would allow an easy tightening (Fig. 18), or by the interposition of a tapped sleeves (Fig. 34) or helical threads, through the pull of a single screw (Fig. 35), by tubular nuts to which access can be had 90 through the orifice of the hub (Fig. 36) and the like.

These devices would be provided with lock-nuts, pins, slotted washers, and the like, 95 for preventing loosening or slackening.

The spacing apart can also be obtained by means of a device which is portable or not, independent from the wheel such as a sort of press the jaws of which move apart under the action of a screw or of a lever; before removing the press, the spacing apart 100 would be maintained by means of ties which can be adjustable or of invariable length.

Packing pieces would be added and adjusted or replaced by longer pieces when it 105 is desired to increase the tension.

It will be possible to give to the hub the forms and sizes which are necessary for fixing the same to the stubshafts of removable 110 wheels.

One of the parts of the hub can slide upon the other or can be packed with slotted conical rings, and fastened by screws, keys, and the like. The two washers of the hub 115 can be connected through tubes, sleeves, and the like, or be separately keyed to the axle or to a part carrying the bearings (Fig. 37).

The possibility of spreading the cones will be particularly appreciated in the use of easily distortable metals, such as aluminum or light alloys.

When the wheel is assembled by means of rivets or bolts, the high initial tension will have the advantage to secure to these rivets or bolts and the contacting surfaces 125 will have a definite setting in position thereby determining, before putting into service, the caulkings necessary to prevent sliding which the shocks of the road would subsequently impose, to the large detriment of the 130

rigidity. The possibility of subsequently increasing this tension will compensate for the complementary plays which occur during the use.

5. What I claim is:

1. The method of constructing metal wheels which comprises forming radially disposed ribs in sheet metal conical members, placing two members with their bases 10 opposite each other, and subjecting said members to stresses tending to augment their conical height.

15. 2. The method of constructing metal wheels, which comprises forming radially disposed ribs in sheet metal conical members, arranging the small ends of two members in fixed relation and with their large ends opposite each other, and subjecting peripheries to stresses tending to bring them 20 nearer together.

25. 3. The method of constructing metal wheels, which comprises forming radially disposed ribs in sheet metal conical members, arranging the small ends of two members in fixed spaced relation and with their large ends opposite each other and subjecting peripheries to stresses sufficient to bring them together.

4. The method of constructing metal wheels, which comprises forming radially 30 disposed ribs in sheet metal conical members, arranging the small ends of two members in fixed spaced relation with their large ends opposite each other, and subjecting 35 their peripheries to stresses sufficient to bring them together and reduce the ribs in said members.

5. The method of constructing metal wheels which comprises flaring the ends of 40 a sheet metal cylinder to form conical cheeks thereon while maintaining the intermediate portion cylindrical, and subjecting the peripheries of the cheeks to stresses tending to bring them together.

6. The method of constructing metal 45 wheels which comprises flaring the ends of a sheet metal cylinder to form conical cheeks therein, forming a plurality of radial ribs in said cheeks, and subjecting the latter to stresses sufficient to augment their conical 50 height.

In testimony that I claim the foregoing as my invention, I have signed my name hereto.

EDOUARD WILFRID BUQUET.
